MANUFACTURE OF BON BON CRACKERS
Philip Steward Powling, Ilford, England, assignor, by
mesne assignments, to Tom Smith & Co. Limited
Filed May 14, 1964, Ser. No. 367,451
10 Claims. (Cl. 93—1)

This invention relates to methods of making bon-bon crackers, sometimes called Christmas crackers or a cosques, which will hereinafter be referred to generally as crackers.

Crackers can be made in a number of ways, using different kinds and arrangements of materials but in a typical method of construction a rectangular sheet of material such as crepe paper, which forms the outside of the finished cracker is assembled with similar sheets of plain paper. A smaller sheet of cardboard forming a stiffener is placed over the middle third of the sheet. A snap, which gives the characteristic "crack" when the cracker is pulled is assembled with the sheets. This assembly of parts is referred to in the trade as a "sticking."

However the sticking is made, it is shaped to form a cylinder and a construction or "waist" is made roughly a third of the distance along the length of the cylinder. The constriction is as tight as may be, and it is made by an operator winding a string around the cylinder, usually twice, and pulling the string endwise. Once the one constriction has been made the filling of the cracker, consisting of novelties, favours, and the like are dropped into the centre of the cylinder and a second waist is formed.

In my copending application No. 24,946/61 (see the corresponding U.S. Patent No. 3,264,797) I have described a method of and apparatus for tying crackers by which this serious limitation can be largely overcome in which the cracker stickings are first made into a cylinder and whilst so formed the "waists" are made by means comprising two relatively movable support members, core-like means presenting a series of spans defining a polygonal figure of a size suitable to permit the insertion therein of a cracker cylinder, each said span extending between an attachment point on the first support member and an attachment point on the second support member, relative movement of said members being effective to cause the size of the figure to be reduced, thereby creating a waist in a cylinder inserted within the figure.

In accordance with the present invention means are provided for rapidly opening the polygon, preferably automatically once the waists have been tied.

Features and advantages of the invention will be apparent from the following description of an embodiment thereof given, by way of example, in conjunction with the accompanying drawings, in which:

FIGURE 1 is a perspective view of the clamping device showing the automatic release mechanism, and

FIGURE 2 is an opposite side view of the release mechanism showing the lever arrangement in more detail.

In the manufacture of crackers by the apparatus of Patent No. 3,264,797, the cracker cylinder is held at its ends by two clamping devices operable by two hand levers and the cylinder is constricted by two waist forming devices operable by two further hand levers, the two clamping devices and two waist forming devices being mounted each on one of two sliding carriages. To release the completed cracker after the waist forming operation, the operator returns the operating levers of the waist forming devices to their initial position, then releases the levers of the clamping devices and finally slides the carriages away from the centre of the machine and removes the cracker.

The present invention affords means by which this

2

operation can be carried out more quickly by arranging that each clamping device is automatically released on operation of the waist forming device.

In the accompanying drawing are shown certain parts of a complete machine of the kind which is otherwise as shown in said U.S. Patent No. 3,264,797, and reference is directed to that patent for a more complete description of the machine and its operation.

For the purpose of the present invention, each clamping device 8 has associated with it a V-shaped lever 60 pivotally mounted on the carriage 7 carrying the device. One arm 60a of the lever is attached to the device by a pin 61 on the device located in a slot 62 formed in the arm 60a, and the other arm 60b is positioned to engage the operating lever 37 of the waist forming device 33 during the end part of its stroke. The device 8 is retained in its operative position by a suitably shaped spring-loaded latch 63 engaging a notch 20b in the disc 20 of the device and also cooperating with an inclined guide 64 attached to the support of device 33. When the arm 60b is engaged by the lever 37, the lever 60 is caused to pivot about its axis, and device 8 to move toward the device 33. This movement firstly brings disc 23 into contact with the spans of cord of device 33, thereby to provide a sharp edge to the outer portions of the waist; and secondly brings the latch 63 into contact with the guide 64 and causes the latch to pivot against its bias thus allowing disc 20 and handle 21 to return automatically under its own bias to an inoperative position.

In this way, the separate operation of returning the levers of the clamping devices is eliminated thereby speeding up the operation of the waist forming apparatus.

In a modification of the arrangement (not shown), the arcuate portion 15a of the upper clamping member 15 has secured to its face a length of rubber strip; the strip is of substantially the same width as portion 15a but its length is such that it extends downwardly on both sides of the mandrel 9. During movement of the clamping members to their operative position, the lower two arcuate portions 15a guide the free ends of the strip around the cylinder until, in the clamping position of the device, they are positioned adjacent each other. It is further arranged that one of the lower clamping members is effective after the other lower member thereby to avoid the formation of folds in the clamped portion of the cracker cylinder.

In a further modification (not shown) the disc 23 has an annular portion of diameter equal to that of the mandrel and extending towards the mandrel; the portion provides a bearing surface for the cracker cylinder in the region of the tapered portion 9a of the mandrel.

I claim:

1. Apparatus for forming the waist in a cracker, comprising support members adapted to embrace a cracker cylinder, waist-forming means operative on relative movement of said members, a device for supporting and clamping an end of the cracker cylinder prior to and during the waist-forming operation and means operative upon relative movement of said members to release said clamping device after the waist has been formed.

2. Apparatus according to claim 1, wherein said clamping device includes a support mandrel for insertion into an end of the cracker cylinder, a plurality of clamping arms co-operating with said mandrel to clamp the cylinder therebetween upon operation of an actuating member and means for locking the actuating member in an operative position.

3. Apparatus according to claim 2, wherein said clamping device is biased to a position away from said waist-forming means and is movable against its bias to release said locking means.

4. Apparatus according to claim 3, wherein said re-

lease means includes a two armed, pivotally mounted, lever, one of said arms being coupled to the clamping device and the other engaging the actuating member of said waist-forming means toward the end of its operative stroke whereby to cause the lever to pivot and the clamping device to move against its bias.

5. Apparatus according to claim 3, wherein said locking means includes a pivotally mounted latch member co-operating with the actuating member of said clamping device and arranged so as to be moved to an inoperative position by a fixed guide member during movement of the device.

6. Apparatus according to claim 1, and including a support ring co-operating with said mandrel and of diameter substantially equal thereto, said ring being inserted into the cracker cylinder to provide a support therefor adjacent to the stiffener during the waist-forming operation and being brought into contact with the waist-forming means prior to the release of said clamping device thereby to provide a well-defined waist.

7. Apparatus according to claim 6, wherein the free-end of said mandrel is tapered to facilitate entry thereof into the cracker cylinder and wherein said ring has an

15

annular portion adapted to surround the tapered portion of the mandrel in the operative position of the clamping device.

5 8. Apparatus according to claim 7, and including three clamping arms, each arm having an arcuate bearing portion.

10 9. Apparatus according to claim 8, wherein one of said arms has secured to its arcuate portion a length of rubber strip which extends on both sides of said mandrel and the free ends of which are positioned adjacent each other in the operative position of the clamping device.

15 10. Apparatus according to claim 9, wherein the other two arms are arranged to move into their operative positions sequentially.
